UNITED STATES PATENT OFFICE.

EDWARD J. HOFF, OF BERKELEY, CALIFORNIA.

SEAT FOR CHAIRS AND THE LIKE.

974,769.

Specification of Letters Patent. Patented Nov. 1, 1910.

Application filed June 15, 1909. Serial No. 502,307.

To all whom it may concern:

Be it known that I, EDWARD J. HOFF, a citizen of the United States, residing at Berkeley, Alameda county, California, have 5 invented certain new and useful Improvements in Seats for Chairs and the Like; and I do hereby declare the following to be a full, clear, and exact description of the invention, such as will enable others skilled 10 in the art to which it appertains to make and use the same.

This invention relates to certain improvements in seats for chairs or the like; and the objects and nature of the invention will 15 be readily understood by those skilled in the art in the light of the following explanation of the accompanying drawings illustrating what I now consider my preferred embodiment from among other formations, arrangements and combinations within the spirit 20 and scope of my invention.

My invention consists in certain novel features in construction and in combinations and arrangements as more fully and particularly described and pointed out herein- 25 after.

Referring to the accompanying drawings:—Figure 1, is a side elevation showing a device of my invention in depressed position, portions of the chair frame being 30 shown in section. Fig. 2, is a similar view showing the seat in normal elevated position. Fig. 3, is a top plan view, the seat proper being broken away, and portions only 35 of the bottom cleats thereof being shown. Fig. 4, is a detail view of certain parts.

My invention contemplates the provision of an efficient (what might be termed) counterbalanced seat for chairs or the like, that 40 is, a vertically movable seat provided with controlling and actuating or lifting means designed to assist the occupant of the chair in rising therefrom, and to break the shock or to cushion the effect of dropping into or 45 sitting down in the chair.

Considerable muscular effort is involved 50 in the operation of rising from a chair to the standing position, and the resulting strain and effort are particularly injurious and wearing in the case of persons who are weak, infirm or crippled, or very stout, or with nursing or other mothers holding infants.

It is the particular object of my invention 55 to provide a vertically movable seat having improved counterbalancing or lifting mech-

anism designed to permit the seat to settle gradually down to lowered or sustaining position under the weight of the occupant of the chair, and to assist the chair occupant 60 in rising by carrying part of the load and to that extent relieving the muscles of the individual; the device being peculiarly advantageous for use in arm chairs inasmuch as the occupant can lift the body by his or 65 her arms when assisted by the counterbalancing or seat lifting mechanism, and thereby relieving the legs and back.

In the particular example illustrated, 1, is the rigid usually open or rectangular horizontal frame of the chair, usually termed the seat frame and rigid with the chair legs or supports. The supporting frame-work of my seat controlling and lifting mechanism is carried by and arranged within the chair 75 frame 1, and comprises a pair of horizontal flat spaced supporting bars 2, set down in frame 1 and extending from front to rear thereof and having upturned vertical ends 20, secured to the inner edges of the front 80 and rear cross bars of frame 1, by screws about as shown so that the frame bars 2, are depressed within frame 1. The horizontal supporting bars 2, carry encircling or rectangular horizontal open frame 3, set down 85 in frame 1, and if so desired formed of a flat strong band of metal set on edge and bent to form the front and rear and usually parallel sides of the frame, and fixed to and on bars 2, by corner brackets having horizontal feet bolted or otherwise secured on the bars 2. The two vertical front brackets 4, are extended upwardly to carry and form bearings for a shaft, while the two rear brackets 5, are extended upwardly to enter 95 and form guiding holders for upwardly projecting coiled expansive cushioning springs 50.

6, is the vertically and angularly movable chair seat which in the present instance is 100 shown diagrammatically, for in practice said seat can be of any suitable or desirable formation, such as upholstered, or plain, or of any suitable finish, material, or body. I show this seat at its under side provided 105 with a pair of spaced depending flanges or cleats 60, extending rearwardly from the front portion thereof, and usually arranged in vertical planes parallel with the vertical planes of the sides of frame 3, and directly 110 over the cushion springs 50.

7, is a horizontal rock shaft arranged

transversely of the front end of the frame 3, and mounted to rock in the projected upper ends of the brackets 4.

A lifting frame is arranged between the seat 6, and the frame 3, and is pivotally joined to the rear portion of the seat and to the frame 3, through the medium of the rock shaft. In the specific example illustrated, this lifting frame consists of a pair of parallel links 8, at their rear ends arranged at the outer side faces of the rear ends of the cleats 60, being pivotally coupled thereto by the horizontal pin or shaft 80. The front portions of the links 8, are loosely mounted 10 to rock or oscillate on the end portions of the rock shaft 7, the front ends 81 of said links being extended and formed with angular edges to engage the top edges of the sides of the frame 3 to limit the upward and 15 forward movement of the seat 6.

82, is a cross bar between and fixed to the links 8 and constituting a stop bar as herein-after set forth.

9, are sleeves arranged on and fixed to the 25 end portions of the rock shaft 7 to rock therewith. The sleeves are formed with rearwardly extending lateral or crank lifting arms 92, arranged between the links 8 of the lifting frame and extending rearwardly beneath the stop bar 82 of the lifting frame, and at their rear ends a distance in rear of the lifting bar 82, said arms 92 are connected to the seat 6 about midway between the front and rear ends thereof. This 30 connection can be established through the medium of stiff comparatively short links 93 at their upper ends pivotally joined to the cleats 60 by cross pin or shaft 94, and at their lower ends loosely or pivotally joined 35 to the rear ends of the lifting arms 92, in any suitable manner or by any suitable means, as by pivot pins 95.

Suitable connections are arranged between the strong contractile coiled lifting springs 45 91, and the lifting shaft 7, to constantly tend to rock the shaft in a direction to raise the seat. Various connections can be employed for this purpose. For instance, merely as an example, I show depending quadrants 90, 50 rigid with the sleeves 9, and flexible pull connections, such as chains 96, at their rear ends secured to the front ends of said springs, and at their front portions secured to the quadrants, to operate in a manner 55 well understood by skilled mechanics.

A brace is provided between the rear bar of the frame 3, and the central or intermediate portion of the rock shaft 7, and in the particular example illustrated, this brace 60 consists of a longitudinally threaded rod 10, passing loosely through the rear end of the frame 3, and secured thereto in longitudinal adjustment by the nuts 11. At its front end this rod is rigid with the central portion of a 65 yoke, Y or fork 12, at its front ends having

open bearings 13 held pressing forwardly against the rock shaft 7 to brace said shaft against buckling or bending under the heavy strain to which it is subjected. Wear can be taken up by the nuts 11 to maintain the parts under the tension desired.

The rear ends of the two heavy strong contractile springs 91 are coupled to and are joined by the head or evener bar 97 adjustable longitudinally of and through which the screw or rod 10, loosely extends. This evener 97 bears forwardly against and is held in the desired adjustment by a large hand wheel or nut 98, arranged on and meshing with the threads of the rod 10, and longitudinally adjustable thereof to vary the tension of the springs 91 and the lifting pull or power thereof on the lifting mechanism.

The springs 91, constantly tend, through the medium of the chains 96, arms 90, and the rock shaft, to elevate the arms 92 and these arms engage the stop bar 82 of the lifting frame 8 and tend to elevate said frame and the rear end of the seat until the ends 81 of said frame engage frame 3 and thereby limit further upward movement of the lifting frame. The links 93, applied to the seat 6 in advance of the pivotal connection 80, between the lifting frame and the rear end of the seat, lift the front end of the seat forwardly and from the intermediate portions of the lifting frame 8, so that in its normal position the seat is elevated a considerable distance from the chair frame 1 and is also projected forwardly therefrom 100 and is inclined downwardly and forwardly from its rear end. The lower front edge of the seat will engage a person about to occupy a seat just above the knees and the initial movements of the body in settling 105 into the seat will tend to swing the seat rearwardly and downwardly against the tension of springs 91 and when the whole weight of the body is thrown on the seat the springs will resist sudden depression of the lifting mechanism, causing the same to settle 110 gradually and without shock upon the cushioning springs 50 and until the links 93 force the arms 92 downwardly from the stop bar 82 permitting the cleats 60 to drop onto said cross bar 82 and the seat to assume its final lowered body supporting position.

When the occupant starts to rise from the chair, usually by assisting with the arms, the front end of the seat will rise until the 115 arms 92 engage the stop bar 82 and frame 8 will thereupon swing upwardly to elevate the seat from its rear end carrying a portion of the weight of the occupant and materially assisting the operation of rising 120 from the chair.

It should be understood that the springs can be easily adjusted to attain the desired tension through the medium of the readily accessible hand wheel 98, and that it is the 130

intention that the springs should be adjusted to suit the particular weight of the person usually occupying the chair or for whom the chair is designed.

- 5 In the particular example illustrated, I have shown my seat lifting or counterbalancing device constructed so as to be applicable to various constructions of chairs, that is so that the device can be made and sold 10 for application to chairs by manufacturers of chairs, or by dealers or artisans to chairs in the home, but I do not so wish to limit my invention.

It is evident that various changes and 15 modifications might be resorted to without departing from the spirit and scope of my invention, and hence I do not wish to limit myself to the particular construction illustrated.

20 What I claim is:—

1. In combination, a supporting frame, a vertically movable seat, a frame at its front end pivotally joined to the front portion of said frame and at its rear end pivotally 25 joined to the rear portion of said seat, vertically movable angle levers carried by said frame and having upwardly and rearwardly extending lifting arms to engage said pivotally joined frame to lift the seat, link connections between the rear ends of said arms 30 and said seat in advance of its rear end, and a seat counterbalancing and lifting spring device carried by said frame and coupled to said angle levers to swing the same to lift 35 the seat.

2. In a chair, in combination, a vertically movable seat, a supporting frame, a swing lifting frame fulcrumed to the supporting frame below the front end of the seat 40 and extended rearwardly and joined to the rear end of the seat to lift the rear end of the seat and project its front end forwardly, a vertically movable lifting frame-elevating member having an independent lifting connection to the seat to elevate its front end, and an actuating spring device comprising 45 a retractive spring and pull connections to said member.

3. In a chair, in combination, a supporting frame, a normally elevated seat having a vertically movable free front end and

mounted at its rear end to swing on a vertically movable transverse axis, supporting means applied to the rear end of the seat and movable in an upwardly and forwardly curving arc to project the seat forwardly and elevate its rear end, a vertically movable actuating member for said means, a seat-swinging connection from said member to said seat for swinging the same on said axis to elevate its forwardly projecting front end, and an actuating retractive spring device having a pull connection to said member.

4. In combination, a supporting frame, a vertically and forwardly movable seat, a vertically swinging frame at its rear end pivotally joined to the rear of said seat and at its front pivotally joined to the front portion of said supporting frame and provided 70 with a stop to limit the upward and forward movement of said seat, a vertically movable lifting arm fulcrumed to said supporting frame and having link connections with said seat in advance of its rear end for elevating 71 the front end of the seat, said arm adapted to engage said swinging frame to elevate the rear end of the seat and to project the seat forwardly, and a retracting spring device provided with a pull connection to said 75 arm for actuating the same.

5. In combination, a supporting frame, a vertically movable seat, a swinging frame pivotally joined to the supporting frame and to the seat for lifting the same and comprising an intermediate cross bar, a vertically movable lifting arm fulcrumed to the supporting frame and arranged beneath and to engage said cross bar and thereby elevate said swinging frame to raise the rear end of 9 the seat, a connection from said lifting arm to the seat to elevate the front end of the seat, and a retractive spring device for elevating said seat provided with an operative pull connection to said arm.

In testimony whereof I affix my signature, in presence of two witnesses.

EDWARD J. HOFF.
